UNITED STATES PATENT OFFICE.

HANS GOLDSCHMIDT, OF ESSEN-ON-THE-RUHR, GERMANY, ASSIGNOR TO GOLDSCHMIDT DETINNING COMPANY, OF NEW YORK, N. Y., A CORPORATION OF NEW JERSEY.

ELECTROLYTIC DETINNING SYSTEM.

1,160,401.

Specification of Letters Patent. Patented Nov. 16, 1915.

Application filed February 5, 1908. Serial No. 414,440.

To all whom it may concern:

Be it known that I, HANS GOLDSCHMIDT, a subject of the King of Prussia, German Emperor, and resident of Essen-on-the-Ruhr, Germany, have invented a certain new and useful Electrolytic Detinning System, of which the following is a specification.

This invention relates to an electrolytic detinning system, and the main object of the invention is to provide an improved apparatus for detinning tin scrap by means of an alkaline electrolyte.

In apparatus of this class as constructed prior to my invention, detinning was practised in single electrolytic cells only, as there was no way known of connecting up the cathode vessels of a group of electrolytic cells in such a manner as to obtain a free flow of the electrolyte through all the vessels of the group. It is well known that such a process is best conducted when the electrolyte is in motion, either constantly or intermittently. In an electrolytic process, however, in which the electrolyte is supplied to a plurality of vats, it is very difficult to maintain the circulation of the lye, and this difficulty is increased by reason of the fact that the connecting pipes are readily coated with tin through electro-deposition, and the normal free passageway for the flow of the electrolyte thereby obstructed. This stoppage of the pipes in the old method of detinning by means of an alkaline electrolyte in a single cathode vessel takes place quite rapidly, because the tin deposited is not dense but is in a spongy condition occupying considerable space. Stoppage of the connecting pipes by this electro-deposited spongy tin is, as is well understood, due to electrolytic action, as the pipes themselves are conductors and are electrically connected by the electrolyte.

I have found as a result of experiments extending over a period of many years, that the circulation of the electrolyte through a series of electrolytic vessels can be maintained and that the temperature of the electrolyte, which is always used in a heated condition, preferably at from 70° C. to 80° C., can also be kept up to the desired point without difficulty, thereby assuring a constant flow of electrolyte of good and sub-

stantially uniform composition without stoppage of the inlet and outlet pipes of the system. This result is accomplished chiefly by connecting up the various electrolytic vessels of the system in such a manner that the electrolyte will not flow in series therethrough, although the electrolytic vessels may, and usually will, be electrically connected in series for the passage of the electric current therethrough. According to my invention, the apparatus is so arranged that the electrolyte will be permitted to flow directly to different electrolytic vessels from a suitable source of supply, the preferred construction being one in which each electrolytic vessel of the system is directly connected with the source of supply and receives its individual supply directly from such source, the various vessels being conveniently connected by branch inlet pipes, one for each vessel, to one or more main inlet pipes connected with a suitable source of supply or reservoir. In large plants the total number of electrolytic vessels may be divided into groups or rows, each constituting a unit, and provision made for operating with one or more units, as required. All the vessels of a single series or unit should be arranged in substantially the same horizontal plane or slightly inclined, in order that the electrolyte may flow readily through the vessels from a common inlet to a common outlet pipe; although different series or units may be placed on different levels or floors of a building.

In order to reduce still further the danger of stoppage of the flow of the electrolyte, it is preferable to make use of inlet pipes which at the points of entrance to the electrolytic vessels are made of insulating material, as by this means all danger of electro-deposition of the tin on the walls of the inlet pipes is avoided.

An important feature of such a system is the determination of the proper sizes of the various pipes of the system through which the electrolyte flows, and the ratio of the pipes at different points in the circulating system to one another, particularly the ratio of the inlet pipes. All of these must be properly chosen and combined in order to obtain an uninterrupted circulation of the electrolyte through the system without re-

ducing materially the temperature of the liquid as it flows through the electrolytic vessels.

Various other features of the system which facilitate the circulation of the electrolyte through the various electrolytic vessels while the electrolyte is maintained at a sufficiently high temperature and in a condition most favorable for even and thorough detinning, and various other features of the system not before referred to, will be hereinafter described in connection with the accompanying drawings, in which:

Figure 1 is a plan illustrating diagrammatically an electrolytic detinning system embodying my invention; Fig. 2 is an end elevation of the same; Fig. 3 is a detail of parts of two electrolytic vessels illustrating the circuit connections thereof; Fig. 4 is a detail illustrating the supply reservoir and means for heating the electrolyte therein; Fig. 5 is a similar view of the return reservoir for the electrolyte and means for heating the electrolyte therein; Fig. 6 is a detail illustrating one of the scrap-containing vessels or baskets supported in place in its cathode vessel.

Similar characters designate like parts in all the figures of the drawings.

Referring first to Fig. 1, which illustrates one way in which the various elements of a system constructed in accordance with my present invention may be combined, 1 designates a source of supply from which an alkaline electrolyte may be delivered to the various electrolytic vessels of the system. This supply reservoir is preferably located above the other elements of the system, in order that the liquid may flow therefrom through the various pipes, vessels, etc. In this case the high supply reservoir is connected by a pipe 2 to two main supply pipes 3 and 4, one of which supplies the alkaline liquid to one series of electrolytic vessels, while the other pipe 4 in a similar manner supplies the electrolyte to another series of vessels. Two branch supply pipes, such as 5 and 6, lead in this case from the main supply pipe 3 to the electrolytic vessels or vats of the first series, these vessels being designated by 7, 8, 9 and 10 respectively. At their ends the branch supply pipes are shown as forked, the forks from the branch supply pipe 5 being designated by 11 and 12, and those from the branch supply pipe 6 by 13 and 14. In a similar manner branch supply pipes 15 and 16 lead from the main supply pipe 4, and each in turn is forked, these forks being designated by 17 and 18 for the branch pipe 15, and by 19 and 20 for the branch pipe 16. The vessels or vats of the second series or row are designated respectively by 21, 22, 23 and 24. The forked inlet pipes 11, 12, 13, 14, 17, 18, 19 and 20 are preferably provided with suitable control

means, such as valves, for governing the flow of the electrolyte into the vessels of the second series. These controlling means or valves for the first series of vessels are designated by 25, and for the second series by 26.

It will be noticed that the pipes which supply the alkaline liquid to the different electrolytic vessels decrease in cross section from the supply reservoir 1 as they approach said vessels. This is a matter of

great importance in order to control the flow of the liquid properly and prevent excessive flow while at the same time assuring a sufficient flow of the liquid at the proper tem-

perature and in the proper condition. I

have found in practice that a good ratio for the respective inlet pipes is to provide a main pipe from the main reservoir of from

three to four inches in diameter, and to

gradually decrease the areas of the inter-

mediate pipes until the forked pipes are

reached, which may have a diameter of about

three-fourths of an inch. Moreover, it is

desirable that the inlet ends of the forked

inlet sections of the piping be located above

the level of the liquid of the respective baths,

the inlet sections themselves being in the

preferred construction made of non-conduct-

ing material, such as hard rubber; these

hard rubber sections, which are designated

by 27, being slipped over the ends of the

forked metallic pipes and preferably also

being slightly above the level of the bath.

When the parts are constructed and com-

bined in the system in this manner stoppage

of inlet pipes due to electro-deposition of

tin, is avoided, and in addition the proper

flow of the liquid, which is always under

considerable pressure because of the eleva-

tion of the supply reservoir, is assured. The

supply reservoir will preferably be of large

size for the purpose of keeping the electro-

lyte at the proper temperature and in as uni-

form a condition as possible. In the con-

struction shown the reservoir 1 (with a re-

turn reservoir which will be hereinafter

specifically described) should be capable of

holding from one-third to one-half of the

whole amount of alkaline liquid contained

in the system. In practice I have used sup-

ply and return reservoirs the combined di-

mensions of which were from about ten to

thirty cubic meters.

In order to maintain the electrolyte in

the supply reservoir 1 at the proper tem-

perature and in the proper condition, the

liquid is preferably heated while in the res-

ervoir, as for example, by means of a heater

such as 28 within said reservoir. This

heater may be of the tubular variety, such

as shown, and may be supplied with steam

through suitable inlet and outlet pipes,

such as 29 and 30. It will be noticed that in

every instance the electrolyte enters each

electrolytic vessel near one end thereof and

at the upper side of the bath. In order that as complete a circulation of the liquid through the bath as possible may be obtained, it is preferable to place the outlet 5 from each vessel at the opposite end thereof and substantially at the bottom of the vessel. This assures a thorough circulation of the alkaline electrolyte from the upper side of the bath at one end thereof to the bottom of the bath at the opposite end of the vessel, from which point it may be permitted to flow out through suitable outlet pipes which in practice may be arranged in a manner analogous to that before described 10 with reference to the inlet pipes and are preferably about two inches in diameter. Thus, two main outlet pipes, such as 31 and 32, run in this case parallel with and below the two rows or series of electrolytic 15 vessels 7 to 10 and 21 to 24, and are connected to the bottoms of the different vessels, there being a separate branch outlet from each vessel of the two series. This branch outlet from each electrolytic vessel 20 is of different type from the branch connections at the inlet side of the system. These branch outlet pipes are constructed as communicating vertical tubes 33 and 34, open at their upper ends and connected at a point 25 just below their upper ends by a short cross pipe 35. The pipe 33 connects with the lower end of the electrolytic vessel, while the pipe 34 is connected directly to the main outlet pipe 31 or 32, as the case may be. 30 Each one of the eight electrolytic vessels in the two series has a connection therefrom to its respective main outlet pipe of the character just described. The object of constructing the outlet from each electrolytic 35 vessel in this manner is to prevent the level of the bath rising above a predetermined point, the parts of the system being so constructed and combined that the electrolyte will overflow from the open upper ends of 40 the pipes 33 and 34 whenever the conditions are such that the electrolyte rises too high in the bath.

The branch outlet pipes just described lead the slightly cooled electrolyte from the 45 main outlet pipes 31 and 32 to a return reservoir, such as 36, in which the liquid may be heated up before it is returned to the supply reservoir. The return reservoir is preferably constructed as shown in Fig. 5, 50 from which it will be seen that it is a tank of large capacity heated by a suitable heater, such as the pipes 37, these pipes being supplied with steam in a manner similar to that before described with reference 55 to the supply reservoir. The steam inlet and outlet pipes of the return reservoir are designated respectively by 38 and 39.

The connections between the various electrolytic vessels and the return reservoir 60 36 may be either open or closed conduits or

pipes; these being interrupted at intervals by tanks, such as 40, to receive the slime resulting from the reaction.

From the return reservoir the circuit through which the electrolyte travels is 65 completed by connections to the high reservoir. These connections preferably include a pump, such as 41, for pumping the electrolyte up into the supply reservoir from the low return reservoir. This pump 70 is preferably placed at a slightly lower level than the low return reservoir in order that the electrolyte may flow by gravity into the pump. The pump can then readily force it up into the high supply reservoir, this being 75 the more readily accomplished when the electrolyte is brought into a more perfectly fluid condition by heating in the low reservoir in the manner just described.

In order to keep the electrolyte of the 80 baths in as fluid a condition as possible (and for the further purpose of electrically isolating the baths) it is desirable in practice to have each of the electrolytic vessels 85 inclosed by a suitable non-conductor of heat 90 and electricity. Both of these objects are accomplished by boxing the vessels, wooden boxes being preferably employed for the purpose, and an insulating air-space being left between the wooden box and the walls 95 of the iron electrolytic vessels. These boxes are designated respectively by 42.

The electrolytic vessels 7 to 10 and 21 to 24 of the system are usually made of cast-iron, and constitute the cathodes of the apparatus. The anodes of the different electrolytic vessels may be of any suitable construction, but I have found in practice that the most desirable for the purpose are scrap-containing vessels or baskets, such as 43, 100 made of sheet metal having openings there-through of sufficient size to prevent the scrap from falling out, but as large as possible so as to reduce the resistance opposed to the passage of the current through each cell of 105 the system. These vessels or baskets, constituting with the scrap the anodes, are also of such a size as is most favorable to the economical use of the current in removing the tin from the scrap. The electrical connections in each cell may be any suitable for the purpose. In this case I have illustrated a plurality of parallel electrical connections from a supply conductor to each anode of a cell. The different cells of the two series 110 are, however, in this construction connected 115 in series with one another.

From a suitable source of energy, such as the generator 44, current is fed to sectional supply conductors, such as 45, there being 120 one of these for each electrolytic cell. Preferably these sectional conductors are normally disconnected from one another, but are connected to the cathodes of adjoining cells. When the scrap-containing vessel or 125 130

anode is in place in a cell the circuit is completed from the sectional conductor 45 at one side of the cathode vessel to the opposite side thereof through the scrap and its container and the electrolyte, and current can flow through the two elements of such cell. In each instance, however, the sectional supply conductor 45 is insulated normally from the cathode, as is the bracket 43.

10 It will be noticed that in the system shown each cathode vessel contains a plurality of anode baskets connected in parallel in the circuit of each electrolytic cell. This permits the total quantity of tin scrap contained in any one cell of the system to be divided up into a plurality of smaller portions.

When it is necessary or desirable for any reason to cut out the electric current from any cell of the system, this may be accomplished by means of a suitable switch, such for example as that shown at 46. This switch serves to connect one end of a sectional supply conductor 45 with an adjoining section of the supply conductor, thus short-circuiting the cell of that particular sectional supply conductor and directly connecting said sections of the supply conductor through the intermediate switch. Each of these sectional conductors 45 is preferably a copper rod or bar insulated from the wall of the cathode vessel. A strip of wood, such as 47, is usually employed as the insulating support for this conductor, said strip being fastened on the edge of the vessel. Each sectional conductor though insulated from its own cathode vessel is of course electrically connected with the other cathode vessel. I prefer to use an angular bond, such as 48, which is soldered or welded to the cathode and has its upper edge in line with that of the sectional conductor of the cathode vessel to which it is fastened. Whenever two adjoining sectional supply conductors are connected by their switch 46, the baskets in the short-circuited cell may be readily removed. Moreover, the controlling valve in the inlet pipe for that cell may be closed, the electrolyte drawn off from the cathode vessel, and that vessel itself put out of action without interrupting the detinning process in the other cells of the series.

Normally the electric current flows without interruption through all the cells of the system. The current used, in order to accomplish the best results, that is, the most economical detinning, will preferably be one of very high amperage, say from eight hundred to one thousand amperes or more per square foot. The use of current of this high density is a matter of much importance and was only determined upon after exhaustive experiments which showed that it was the

most desirable under all the conditions present in a large commercial detinning plant.

The composition of the electrolyte for practical detinning on a commercial scale is also a matter of very great importance. I prefer to use a mixture of stannate of soda and caustic soda with an excess of the caustic soda. The alkaline electrolyte contains also carbonate of soda, as the alkali takes up and unites with carbonic acid in the air. With an electrolyte of this composition the process carried on is a continuous one because of the regeneration of the liquid as it circulates through the system.

What I claim is:

1. In a detinning system, the combination with a series of electrolytic vessels, and with means for passing an electric current through said vessels, of a main supply pipe, branch supply pipes leading from said main supply pipe to each of said vessels and terminating in sections of insulating material at each vessel, and means for passing an electrolyte through said supply pipes and vessels.

2. In a detinning system, the combination with a series of electrolytic vessels, and with means for passing an electric current through said vessels, of a main supply pipe, branch supply pipes leading from said main supply pipe to each of said vessels and terminating in sections of insulating material at each vessel, and means for passing an electrolyte through said supply pipes and vessels from one end to the other of each vessel.

3. In a detinning system, the combination with a series of electrolytic vessels, and with means for passing electric current of very high amperage through each of said vessels, of individual electric switches for short circuiting said vessels respectively, a high supply reservoir, connecting means between said supply reservoir and said vessels for delivering separate supplies of electrolyte to different vessels of said series from said reservoir, a low return reservoir, connecting means between said vessels and said return reservoir, and means for returning the electrolyte from the return reservoir to the supply reservoir.

4. In a detinning system, the combination with a series of electrolytic vessels, and with means for passing electric current of very high amperage through each of said vessels, of individual electric switches for short circuiting said vessels respectively, a high supply reservoir, connecting means between said supply reservoir and said vessels for delivering separate supplies of electrolyte to different vessels of said series from said reservoir, a low return reservoir, connecting means between said vessels and said return reservoir, means for returning the electrolyte from the return reservoir to the supply

reservoir, and individual controlling means for governing the flow of the electrolyte at said vessels respectively.

5. In a detinning system, the combination with a series of electrolytic vessels, and with means for passing an electric current through said vessels, of a high supply reservoir, connecting means between said supply reservoir and said vessels for delivering 10 separate supplies of electrolyte to different vessels of said series from said reservoir, a low return reservoir, connecting means between said vessels and said return reservoir, means for returning the electrolyte from 15 the return reservoir to the supply reservoir, and one or more slime-tanks in the connections between said vessels and the return reservoir.

6. In a system of the character described, 20 in combination, a vat, a closed conduit circulating system for circulating an electrolyte therethrough, and enlargements in the conduits for collecting slime from the vat.

7. In a system of the character described, 25 in combination, a closed conduit circulating system for circulating an electrolyte therethrough, and enlargements in the return conduits of the system for collecting slime from the vat.

8. In a system of the character described, 30 in combination, a vat, a closed conduit circulating system for circulating an electrolyte therethrough, and slime tanks for collecting slime from the vat.

9. In a detinning system, a plurality of 35 electrolytic vessels each having a cathode and a plurality of anodes electrically connected in parallel, electrical series connections between the anodes and cathodes of separate vessels, and means to supply the 40 electrolyte to and withdraw it from each vessel separately.

10. In a detinning system, a plurality of electrolytic vessels, electric connections between said vessels, means to short circuit 45 any one of said vessels, means to supply the electrolyte to each of said vessels separately from a common source, and means to cut off the supply of the electrolyte to any one of said vessels. 50
